UNITED STATES PATENT OFFICE.

EMANUEL HENRIKSON, OF BRIDGEPORT, CONNECTICUT.

DOUBLE-ACTING RATCHET.

No. 828,884.

Specification of Letters Patent.

Patented Aug. 21, 1906.

Application filed January 25, 1906. Serial No. 297,787.

To all whom it may concern:

Be it known that I, EMANUEL HENRIKSON, a citizen of the United States, and a resident of Bridgeport, in the county of Fairfield and State of Connecticut, have invented certain new and useful Improvements in Double-Acting Ratchets, of which the following is a specification.

This invention relates to new and useful improvements in ratchets, and is designed with special reference to use upon boring-mills, planers, and other machine-tools. The feed-shafts of machine-tools of the above class frequently require a slight movement for the fine setting of adjustment of the tool. This has heretofore been accomplished in many instances by a detachable hand-crank applied to the end of the shaft, which was inconvenient and otherwise objectionable.

It is therefore the purpose of my invention to provide an improved double-acting ratchet for making the several slight adjustments of the tool required at times; to design it as a fixed attachment to the feed-shafts of the machine and adjacent to the saddle, thus convenient to the operator; to construct it as a lever-operating device adapted for engagement to operate in both a forward and backward direction and having a normal intermediate disconnected position, which the tool automatically assumes when released.

Upon the accompanying drawings, forming a part of this specification, similar characters of reference denote like or corresponding parts throughout the several figures, and of which

Figure 1 shows a perspective view of the face and end of a portion of a cross-rail and saddle of a boring-mill with a pair of my improved ratchets attached to the feed-shafts and saddle. Fig. 2 shows, on an enlarged scale, a side elevation of my ratchet disconnected. Fig. 3 is a central longitudinal section through the ratchet and taken on line 3 3 of Fig. 3. Fig. 4 is a horizontal section of the ratchet, taken on line 4 4 of Fig. 3, the operating-lever, however, being shown in an engaged position and the sleeve containing a square hole instead of a round, as seen in Figs. 2 and 3.

Referring in detail to the characters of reference marked upon the drawings, A indicates a portion of a cross-rail such as is commonly used on boring-mills.

B represents the near side portion of a saddle slidably mounted upon the rail.

C designates a threaded feed-shaft which engages and operates the saddle along the rail in any well-known or preferred manner, 60 and D is a feed-shaft which connects with and operates the tool-head. (Not shown.) Both of these shafts are commonly used upon boring-mills, planers, and other machine-tools and are driven through gear connections inclosed within the casing E and obviously constitute no part of my invention.

The ratchet proper comprises an annular sleeve a, which may be provided with either a keyway b for attachment to a shaft, as seen in Fig. 3, or may contain a shouldered hole c, as seen in Fig. 4. The former construction is obviously best adapted for round shafts, such as are shown in Fig. 1, while the other design is especially adapted for squared shafts. By this or an equivalent means the sleeve may be slidably attached to a shaft, thus freely turning therewith when the shaft is driven, but likewise adapted to turn the shaft through the operation of the connecting members of the ratchet. d indicates an annular shoulder upon the sleeve, intermediate of which and an attached collar e bracket f of the saddle B is engaged to connect the ratchet and saddle and insure a longitudinal movement of the ratchet with the saddle. The sleeve further contains a series of teeth r upon its periphery for engagement by the correspondingly-toothed end of the plunger g, slidably mounted in a pocket h of an arm i, journaled upon the sleeve a and intermediate of its shoulder d and an outer collar j, threadably attached thereto, as is clearly shown in Fig. 3.

The plunger is mounted in the arm radially with respect to the axis of the sleeve, and consequently has a direct movement and grip upon the toothed peripheral surface. The outer end of the plunger bears a head, forming an annular shoulder k, intermediate of which and a shoulder l of the pocket h is mounted a spring m, which normally tends to hold the plunger distended and out of engagement with the sleeve. The outer end of the head of the plunger contains a transverse concave or half-round recess n, with side shoulders o on either side. The operating-lever p, hinged upon the pin q, secured in the end of arm i, contains a corresponding convex end to normally rest in said

recess of the plunger, while the transverse side shoulders *s* engage the shoulders *o* of the said plunger. From the foregoing construction it will be seen that the action of the 5 spring upon the plunger not only serves to normally hold it disengaged from the sleeve, but also to hold its ends *o* tight against both shoulders *s* of the lever, thus normally retaining the lever in an intermediate position 10 straight in line with the arm and movements of the plunger. This normal position of the parts leaves the sleeve disengaged and free to turn with the operating movements of the shaft upon which it is mounted, but always 15 in position to be quickly operated by hand—as, for instance, in the setting of the tool while the shafts are at rest and preparatory to beginning work. This construction permits of a movement of the sleeve and shaft 20 in either direction by simply operating the lever correspondingly, it being apparent that if the lever be thrust upward, as seen in full lines in Fig. 4, the upper shoulders are engaged and the plunger operated against the action of the spring to engage and turn 25 the sleeve in a forward direction, while if it be similarly pressed in the opposite direction (see dotted line, Fig. 4) the plunger is similarly operated to engage the sleeve, but 30 turning it in the opposite direction. This construction therefore forms a double-acting ratchet with an automatic release, comprising principally, besides the sleeve, a single plunger, spring, and lever.

35 It will of course be apparent to those skilled in the art that my invention is equally applicable to many other uses than that to which I have shown it applied, and consequently I do not wish to be limited in that respect.

Having thus described my invention, what I claim, and desire to secure by Letters Patent, is—

40 1. In a ratchet of the class described, the combination of a sleeve, an arm pivoted

thereon, a spring-actuated plunger mounted therein to engage the sleeve, a lever pivoted in the arm having shoulders engaged by the plunger to normally retain the lever in an intermediate position and adapted to operate 50 the plunger by either a forward or backward movement of the lever.

2. In a ratchet of the class described, the combination with a sleeve having a toothed periphery, of an arm pivotally mounted 55 thereon, a plunger mounted in the arm and adapted to engage the teeth of the sleeve, means to normally hold the plunger away from the teeth, a lever pivoted in the arm adapted to operate the plunger to engage 60 said sleeve by either a forward or backward movement.

3. The combination of an arm having a bore therein to permit of its pivotal attachment, a pocket in such arm, a spring-actuated plunger mounted in the pocket, a lever pivoted in the arm having shoulders engaged by the plunger to normally retain the lever 65 in an intermediate position and adapted to operate the plunger against the action of its 70 spring by either a forward or backward movement of its lever.

4. In a ratchet of the class described, the combination with a sleeve adapted for engagement with a shaft, of an arm pivoted 75 upon the sleeve having a longitudinal socket therein, a plunger mounted in the socket and having a divided head forming oppositely-located shoulders, a lever pivoted in the arm and having shoulders to register with those 80 of the head of the plunger and a spring to normally hold the plunger distended and the shoulders engaged.

Signed at Bridgeport, in the county of Fairfield and State of Connecticut, this 15th 85 day of January, A. D. 1906.

EMANUEL HENRIKSON.
